UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

CYLINDER LOCK.

Application filed April 26, 1921. Serial No. 464,715.

To all whom it may concern:

Be it known that I, SAMUEL SEGAL, a citizen of the United States, and a resident of New York, in the county of New York and 5 State of New York, have invented certain new and useful Improvements in Cylinder Locks, of which the following is a specification.

My invention relates to cylinder or pin 10 tumbler locks, the invention relating more particularly to the manner in which the cylinder itself is held or secured to the door or other support to which the lock is applied. The present invention constitutes in part improvements 15 on the invention embodied in my prior Patent No. 1,399,159, dated Dec. 6, 1921.

The principal object of the invention is the production in a lock of the character described 20 of simple and effective means adapted to hold and fasten the lock cylinder in the usual opening in the door provided to receive the same.

A further object of the invention is the provision 25 of a lock cylinder carrying a ring or escutcheon adapted to engage the face of the door, which ring or escutcheon shall be adapted to engage the cylinder fastening means hereinbefore referred to and to move 30 said fastening means into a position permitting the cylinder to be inserted within the opening in the door.

A further object of the invention is the production 35 of a lock cylinder provided with a face plate and with fastening means both acting to prevent the removal of a ring or escutcheon loosely carried by said cylinder.

A still further object of the invention is the production 40 of a lock casing having a cover plate or other wall provided with novel means adapted to engage the wall of the opening which receives the lock cylinder to facilitate the mounting of the lock casing on the door in the proper position.

Still other and further objects and advantages will appear from the accompanying description, the invention consisting in the novel parts and combinations of parts hereinafter more particularly described and 50 then specified in the claims.

In the accompanying drawing showing a practical embodiment of the invention:

Fig. 1 is a section taken through a door showing the lock applied thereto.

Fig. 2 is a plan view of the lock cylinder

and adjacent parts including the cylinder fastener.

Fig. 3 is a side elevation of the parts shown in Fig. 2.

Fig. 4 is a horizontal section on the line 4—4 of Fig. 3.

Referring in detail to the drawings:

1 indicates a door and 2 the door frame. Said door is provided with an annular opening 3 for receiving the lock cylinder to be 65 presently described. The lock casing is indicated at 4 and contains the locking mechanism and is provided with the usual operating knob 5 as shown. 6 indicates the rear wall or cover plate of said casing which is 70 provided with flanges 7 preferably cut out of the material of said rear wall and then bent over in a plane at right angles to the plane of said rear wall. These flanges are adapted to engage the wall of the opening 3 whereby the 75 lock casing may be conveniently and expeditiously mounted on the door by suitable screws or bolts (not shown) in the proper position as respects said opening 3, said flanges 7 acting as guides in an obvious manner whereby the proper position of the casing is obtained.

8 indicates the cylinder of an ordinary pin tumbler lock supporting pin tumblers (not shown) in the tumbler housing 9 thereof. Said cylinder is provided with enlarged portion 10, as shown, and it has mounted therein a key plug 11 held from withdrawal forwardly through said cylinder by an end plate 12 secured to said plug by suitable 80 screws and engaging the rear end of said cylinder. 13 indicates a spindle secured to said key plug 11 and extending through a slot in the end plate 12 and rearwardly through the wall 6 of the casing 4 and into 85 said casing where it operatively engages the lock mechanism to actuate the same when a key is inserted in the key plug 11 from without the door to effect a rotation of said plug and spindle.

The cylinder 8 is provided with an annular face plate 14 preferably integral therewith and of a size permitting it to fit within the annular opening 3. Said face plate is provided with the usual annular opening (not shown) receiving the key plug within the cylinder 8. 15 indicates a ring or escutcheon loosely carried by said cylinder and encircling the face plate 14 and adapted to engage the face of the door 1 when 110

the parts are in proper mounted position. Said ring or escutcheon is provided with an annular inwardly turned flange 16 adapted to engage the rear side of said face plate and 5 providing a seat therefor. The cylinder 8 is also provided with laterally extending ears 17 preferably integral with said cylinder and having screw-threaded perforations therein receiving the screws 18. The sides 10 of the forward ends of the shanks of said screws are preferably supported, for the purpose of strength, by the enlarged portions 10 of the cylinder, said enlarged portions at their sides being threaded to mesh 15 with the threads on the screws.

19 indicates my improved cylinder fasteners comprising plates having a plurality of outwardly turned prongs 20 at the upper ends thereof. In the embodiment of the invention illustrated I have shown three prongs with the intermediate or middle prong appreciably longer than the outside prongs whereby a biting engagement of all the prongs with the wall of the opening 3 25 will always be effected, said opening being an annular one as has previously been described. The said cylinder fasteners 19 are provided with slots 21 therein receiving ears 22 which are preferably integral 30 with said cylinder and the ends of which are bent over as shown in Fig. 1, whereby a pivoted connection is provided between said cylinder and said cylinder fasteners.

35 The said cylinder fasteners 19 and the face plate 14 of the cylinder provide stops to prevent withdrawal of the ring or escutcheon from the cylinder in either direction. This makes for convenience in the shipping 40 of the parts and obviates any possibility of loss of the ring or escutcheon. It also insures against the mounting of the ring or escutcheon in the wrong position on the cylinder as it is already loosely mounted thereon and it is impossible to reverse its position.

45 To properly position or mount the cylinder within the opening 3, assuming the lock casing 4 has not been fastened to the door, the screws 18 are unscrewed and brought 50 into extreme inner position within the ears 17. The cylinder fasteners 19 are then swung inwardly on their pivots which may be accomplished by holding said cylinder and pressing against the ring or escutcheon 55 15 whereby the flange 16 thereof will engage and press against the cylinder fasteners swinging them on their pivots, whereby their adjacent sides or backs are substantially parallel. The cylinder is then inserted 60 in the opening, the escutcheon held against the face of the door and the cylinder pressed inwardly to cause its face plate to seat against the flange 16. The screws 18 are then threaded or screwed forwardly 65 through the perforated ears 17 whereby the

forward end thereof will engage the cylinder fasteners, thereby forcing said fasteners to swing or spread outwardly whereby the prongs 20 thereof will bite into the wall of the opening 3. The spreading outwardly 70 of said fasteners and the biting of the prongs 20 into the wall of the opening by actuation of the screws 18 acts in an obvious manner to simultaneously draw the cylinder inwardly through said opening, 75 whereby the face plate 14 thereof is tightly clamped against the flange 16 of the escutcheon and the escutcheon is tightly clamped against the face of the door.

80 When the cylinder is mounted in position within the opening 3 in the manner just described it is locked against withdrawal through said opening or against rotation therein until the screws 18 are unthreaded or unscrewed and the prongs 20 of the cylinder fasteners are released from biting engagement with the wall of the opening. After the cylinder is properly mounted the lock casing may be fastened to the door in 85 the manner previously explained.

90 What I claim as my invention is:—

1. In a lock, the combination with a wall having an opening therein and a lock cylinder within said opening, a lock casing containing the lock mechanism and flanges cut 95 out of the material of a wall of said casing and bent over to extend outwardly from said casing and adapted to engage the wall of said opening and acting as guides to permit said casing to be mounted in proper position on said wall.

100 2. In a lock, the combination with a wall having an opening therein, of a cylinder associated with said wall, a face plate on said cylinder, an escutcheon loosely carried by 105 said cylinder, a flange on said escutcheon providing a seat for said face plate and means engaging said cylinder and the wall of said opening to lock said cylinder in position and adapted upon actuation thereof 110 to clamp said face plate against said flange and said escutcheon against the face of said wall.

115 3. In a lock, the combination with a wall having an opening therein, of a cylinder within said opening, an escutcheon loosely carried by said cylinder, a flange on said escutcheon and fastening means engaging said cylinder and adapted to bite into the wall of said opening to lock said cylinder against withdrawal, said fastening means being also adapted upon actuation thereof 120 to draw said cylinder inwardly in said opening whereby it will be clamped against the flange of said escutcheon and said escutcheon will be clamped against the face of said wall.

125 4. In a lock, the combination with a wall having an opening therein, of a cylinder within said opening, an escutcheon comprising

- ing a ring loosely carried by said cylinder, fastening means pivoted to said cylinder and means carried by said cylinder adapted, upon actuation, to force said fastening means to bite into the wall of said opening whereby said cylinder will be clamped against said escutcheon and said escutcheon will be clamped against the face of said wall. 40
- 5 5. In a lock, the combination with a wall having an opening therein, of a cylinder, a face plate on said cylinder, fastening means carried by said cylinder adapted to engage the wall of said opening to lock said cylinder against withdrawal from said opening and an escutcheon loosely carried by said cylinder and prevented from removal therefrom by said face plate and said fastening means. 50
- 10 6. In a lock, the combination with a wall having an opening therein, of a cylinder within said opening, a face plate on said cylinder, fastening means adapted to bite into the wall of said opening to lock said cylinder in position within said opening and an escutcheon comprising a ring loosely carried by said cylinder intermediate said face plate and said fastening means and prevented from removal from said cylinder by said face plate and said fastening means. 60
- 15 7. In a lock, the combination with a wall having an opening therein, of a cylinder, fastening means carried by said cylinder adapted to engage the wall of said opening to lock said cylinder in position within said opening, said plate being provided with a slot therein and an ear secured to said cylinder and extending through said slot and bent over adjacent said plate whereby a pivoted connection is provided between said plate and said cylinder. 65
- 20 8. In a lock, the combination with a wall having an opening therein, of a cylinder within said opening, an ear on said cylinder, a cylinder fastener carried by said cylinder and means carried by said ear and engaging and supported by the side of said cylinder and adapted to force said cylinder fastener into the wall of said opening. 70
- 25 9. In a lock, the combination with a wall having an opening therein, of a cylinder within said opening, an ear on said cylinder, a cylinder fastener carried by said cylinder and means carried by said ear and engaging and supported by the side of said cylinder and adapted to force said cylinder fastener into the wall of said opening. 80
- 30 10. In a lock, the combination with a wall having an opening therein, of a cylinder within said opening, an ear on said cylinder, a cylinder fastener carried by said cylinder and means carried by said ear and engaging and supported by the side of said cylinder and adapted to force said cylinder fastener into the wall of said opening. 85
- 35 7. In a lock, the combination with a wall having an opening therein, of a cylinder, fastening means carried by said cylinder adapted to engage the wall of said opening to lock said cylinder in position within said opening and an escutcheon loosely carried by said cylinder and adapted to be pressed against said fastening means to force the
